US0D1031844S

(12) **United States Design Patent** (10) **Patent No.:** **US D1,031,844 S**
(45) **Date of Patent:** **** Jun. 18, 2024**

(54) **REMOTE CONTROL PAGE TURNER**

(71) Applicant: **Shenzhen Boyangyu Technology Co., Ltd.**, Shenzhen (CN)

(72) Inventor: **Hengjun Liu**, Linqing (CN)

(73) Assignee: **Shenzhen Boyangyu Technology Co., Ltd.**, Shenzhen (CN)

(**) Term: **15 Years**

(21) Appl. No.: **29/907,114**

(22) Filed: **Jan. 4, 2024**

(51) LOC (14) Cl. **14-03**

(52) U.S. Cl.

USPC **D13/168**

(58) **Field of Classification Search**

USPC D19/99, 202, 203; D13/158, 162, 168, D13/171, 173; D17/9, 99; D14/218, D14/388, 412

(57) **CLAIM**

The ornamental design for a remote control page turner, as shown and described.

DESCRIPTION

FIG. 1 is a top, front and right side perspective view of a remote control page turner, showing my new design; FIG. 2 is a bottom, rear and left side perspective view of therefore;

FIG. 3 is a bottom, front and right side perspective view of therefore;

FIG. 4 is a right side perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The broken lines show the features of the remote control page turner that form no part of the claimed design.

1 Claim, 10 Drawing Sheets
